UNITED STATES PATENT OFFICE.

FRANK CLEMENS, OF LAFAYETTE, INDIANA.

HAT AND COAT RACK.

SPECIFICATION forming part of Letters Patent No. 379,152, dated March 6, 1888.

Application filed August 2, 1887. Serial No. 245,999. (No model.)

To all whom it may concern:

Be it known that I, FRANK CLEMENS, of Lafayette, in the county of Tippecanoe and State of Indiana, have invented certain new and useful Improvements in Hat and Coat Racks, of which the following is a full, clear, and exact specification, reference being had to the accompanying drawing, in which—

The figure shows in perspective one of my improved hat and coat racks.

The object of the invention is to provide a neat, strong, and cheap hat-rack; and the invention consists in the construction and arrangement of parts, as will be hereinafter fully described, and specifically pointed out in the claim.

1 is a single piece of wire forming the back piece and bent upward twice between its ends to form the attaching-arms 2 2, having eyes 3 3 at their bends, and the ends of the wire are bent forward at right angles to the arms 2 and then back upon themselves to form the hat or coat arms or hooks 13, the extremities of the wire being bent to form hooks 15 at right angles to the back piece. These rings bear against the wall or article to which the rack is secured by

screws 7, and afford great support for the end arms, 13, as well as serving as hooks upon which coats may be suspended by their supporting-loops. The wire is also bent at its center to form the arm 14 parallel with the arms 13.

Having thus described my invention, what I claim as new, and desire to secure by Letters Patent, is—

As an improved article of manufacture, a hat and coat rack formed of a single wire bent outward at its center and ends to form the arms 13 14, and upwardly between its center and ends to form the attaching-arms 2 2, having eyes 3 3, the outer bends or sections of the arms 13 13 being formed at their inner ends, which are the extremities of the wire, with hooks 15 15 to bear against the wall or support and strengthen said arms and also allow 45 of coats being suspended therefrom, substantially as set forth.

35

FRANK CLEMENS.
